SKI BINDING

Robert Van Brunt, Newark, N. J.

Application February 25, 1937, Serial No. 127,600

1 Claim. (Cl. 280—11.35)

This invention relates to improvements in ski bindings and more particularly to the toe engaging portions of such devices.

An object of the invention is to provide a simple, sturdy and efficient ski binding which may be manufactured economically.

Ski bindings have been provided which include two adjustable toe engaging elements or toe pieces each consisting of a vertical flange extending upward from a horizontal base portion, the toe engaging elements being adjustable to accommodate different shapes and widths of toes of various kinds of ski shoes or boots, said elements being held against accidental displacements by a removable locking plate held on the ski by screws, the locking plate extending over the horizontal portion of the toe engaging elements.

Some of the features of the invention relate to the improvements of the interlocking means, between the locking plate and the toe engaging elements, to afford maximum strength and facilitate assembling of the locking plate, when making an adjustment of the toe engaging elements.

Another feature relates to hold down lugs, on the toe engaging elements, which extend over the edges of the sole of the ski shoe, means being provided whereby these lugs are made adjustable to accommodate various thicknesses of the soles.

A further feature relates to means to prevent accidental displacement and dislodgement of the hold down lugs from their adjusted positions.

In the accompanying drawing which forms part of the specification:

Fig. 1 is a top plan view of the device attached to a portion of a ski;

Fig. 2 is a vertical section taken on the line 2—2 of Fig. 1;

Fig. 3 is a view, similar to Fig. 1, but shows a different adjustment of the toe engaging pieces; and

Fig. 4 is a detail end view showing the teeth of a portion of one of the toe engaging elements engaging the teeth of a portion of the locking plate.

Similar reference characters represent similar parts throughout the several views.

The ski binding of this invention includes two toe engaging pieces or elements 5, each having a vertical flange 6 to engage the opposite side edges of a sole of a ski shoe or boot, not shown. From the lower end of each flange 6 extends, horizontally, another flange 7 having elongated slots 8. The flanges 7 rest upon the ski 9 and are held in place by a locking plate 10 having holes

11 therein. Screws 12 extend through the holes 11 of said locking plate 10 and through the slots 8 of the toe piece flanges 7, and are threaded into the ski 9 to secure the toe engaging elements 5 in any position to which they may be 5 adjusted.

After the toe or fore part of the ski shoe has been inserted between the vertical flanges 6, the ski may be secured to the shoe by the usual heel engaging device including two straps A extending forwardly therefrom, each strap having at its forward end a metal hook A' engaging a stud A2 secured to the outer side of the flange 6, one of the straps being provided with the usual lever to produce a pull on both straps to thereby push 15 the ski shoe forwardly to fit tightly between the flanges 6 of the toe engaging pieces 5.

The toe engaging elements 5 are interlocked with the plate 10 by upward extending teeth 15 and 16 of the flanges 7 and thus any accidental, 20 lateral shifting of the toe engaging devices 5 is prevented. The teeth 13 and 15, at the left hand end of Fig. 2, of the flanges 7 and the plate 10, may be slightly rounded so as not to present objectionable corners to the sole of the 25 shoe while the latter is being pushed forward in the binding devices.

In Fig. 1, the toe engaging elements 5 are set in their closest adjustment or, in other words, for the smallest shoe which the device can accommodate. When the adjustment is to be changed for a larger shoe the screws 12 are released sufficiently to permit the plate 10 to be lifted high enough to disengage the teeth 13 and 14 from the teeth 15 and 16. The toe engaging 35 elements 5 may then be moved outwardly, as at the upper portion of Fig. 3, to occupy a position parallel to the former position in Fig. 1, or one of the elements 5 may be adjusted angularly with reference to its former position or 40 with reference to the side edge of the plate 10. To do this it is swung outwardly only at one end to the position shown in the lower portion of Fig. 3. After the teeth 13 and 14 have been properly registered with the spaces between the 45 teeth 15 and 16 of the plate 10, the latter may be lowered and the screws are subsequently tightened to lock the toe engaging elements in their changed positions.

It is important, from a standpoint of strength, 50 that as many teeth of the elements 5 and plate 10 cooperating at a time, therefore as many of the teeth 13 and 14 of the plate are arranged in a straight row similarly to the teeth 15 and 16 which are all arranged in straight rows on the ad- 55

justable elements 5. Since angular adjustments of the elements 5, as shown in the lower part of Fig. 3, are sometimes desired, the rows of teeth 13 and 14 are curved at their ends to facilitate such angular adjustments.

From the foregoing, and by an inspection of Fig. 1, it will be understood and observed that the plate 10 has the teeth 13, at one edge thereof, arranged in a row the middle portion of which 10 is straight and the end portions are curved, that the teeth 14 at the opposite edge of the plate are arranged in two rows each having a straight outer end portion and a curved inner end portion, the straight portions of the rows of teeth 14 being 15 parallel with the straight portion of the row of teeth 13. This arrangement of the teeth 13 and 14 permits a maxim number of teeth to be active when the toe engaging elements 5, on which the teeth 15 and 16 are arranged in straight parallel rows, are adjusted to positions parallel to the side edges of the plate 10. It also permits the angular adjustment of the toe engaging elements, 20 as above described, and illustrated in the lower part of Fig. 3.

It will be observed, by an inspection of Figs. 1 and 2, that the teeth 15 and 16 extend upwardly and slightly outwardly from the flanges 7 of elements 5. This facilitates assembly of the elements 5 with the plate 10. To further facilitate 30 such assembly the teeth on the flanges 5 are tapered or in other words narrower at their upper ends, see Fig. 4, so that the teeth 13 of the plate 10 may find their way down between the teeth 15 of the flange 7 more readily.

It will also be observed that the inner corners, 35 formed by the teeth 15 and 16, and the body of the plate 10, engage the lower corners extending between the teeth 13 and 14 of the plate 10. Therefore each of the teeth 15 and 16 may act 40 as an individual stop cooperating with the plate 10, to prevent relative lengthwise shifting of the toe engaging elements 5 with respect to said plate 10.

Hold down lugs 17 are provided on the flanges 45 6, of the toe engaging plates 5, and extend over the edges of the shoe sole to firmly hold down the shoe in the binding device.

It is a feature of the invention to provide means 50 to facilitate an adjustment of these hold down lugs 17 in accordance with various thicknesses of the soles of different kinds of ski shoes. To this end each hold down flange 17 has at one side thereof, a downwardly extending locking portion 55 or shank 18 provided with teeth 19 at its opposite edges. These teeth cooperate with teeth 20, formed at the opposite sides of a slot 21, in the flange 6, to prevent accidental or vertical shifting of the lug 17 from its adjusted position.

To hold the shank 18 in the slot 21 and thus 60 prevent accidental removal therefrom, there is provided a screw 22, extending through a sufficiently large aperture 23 of a washer element 24,

and into a threaded hole in the shank 18. By means of the screw 22, the hold down lug 17 may be drawn tightly against the inner side of the vertical flange 6 to prevent accidental loosening of the lug element comprising the members 17 and 18 and thus hold the shank 18 in the slot 21.

There is exerted a tremendous pull by the straps A, which may otherwise tear out the studs A2 from the flanges 6. This is prevented however, by the washer elements 24 which engage the outer 10 ends of said studs A2 where they are pivotally attached. Thus it will be understood that the washer elements 24 serve as braces for the studs A2. Another advantage of this construction is that the washer elements 24 are always attached 15 to the device and cannot become misplaced or lost while making an adjustment of the hold down lugs 17.

In order to make an adjustment of the hold 20 down element 17-18 for a different thickness of sole, the screw 22 is first removed, the hold down element is then detached from the flange 6 by moving the lug away from the inner face of the vertical flange 6 to thus disengage the teeth 19 from the teeth 20 of the slot 21. The shank 18 25 may then be reinserted into the slot 21 with the lug 17 at the desired position to accommodate the sole. The lug element 17-18 may then be secured in this position by the screw 22. The hold 30 down lugs 17 may be slightly curved, as shown 35 in Fig. 2, so that the sole may be readily pushed thereunder.

Having thus described the invention it will be understood that alterations and changes may be made without departing from the spirit of the 35 invention as defined in the appended claim.

I claim:

In a ski binding, the combination of two adjustable toe engaging plates, a locking plate to hold the toe engaging plates in their adjusted positions on the ski, and means to hold the locking plate firmly on the ski, the toe engaging plates having teeth at their front and rear edges to cooperate with teeth on the front and rear edges of the locking plate to prevent sidewise displacement of the toe engaging plates and to prevent 45 accidental shifting of the toe engaging plates lengthwise of the ski, the teeth on the toe engaging plates being arranged in two straight parallel rows, the teeth on the rear edge of the locking 50 plate being arranged in a row having a straight middle portion and two curved portions one at each end of said middle portion, the teeth at the front edge of the locking plate being arranged in two separate rows each having a straight outer 55 end portion which is parallel with said middle portion of the row at the rear end of the locking plate, each row of teeth at the front end of the locking plate having also a curved inner end portion.

ROBERT VAN BRUNT.
